UNITED STATES PATENT OFFICE.

EDWARD L. HUBBARD, OF OAKLAND, CALIFORNIA.

GOLF CLUB.

Application filed April 6, 1925. Serial No. 20,937.

This invention relates to golf clubs and more particularly to improvements in the head of the club and to an improved means for securely attaching the shaft to the head.

- 5 An object of the invention is to improve the construction of heads for golf clubs which are moulded of a phenol composition by embedding a filler of comparatively light weight material and reinforcing strips in 10 the moulded head at certain locations whereby to give better balance to the club, to reduce the weight of the head, and to strengthen the parts at the points of greatest strain.
- 15 Reference may be had to Patent #1,515, 390 granted to me on Nov. 11, 1924, for a description of a golf club having a reinforced phenol composition head.

To lighten and strengthen a club head of 20 the above type I preferably insert a block of wood, around which is found a layer of cord or of open-mesh cloth, the wood block and the cord or cloth being painted with a phenol insulating varnish or cement. Outside of 25 this, and to be spaced therefrom, I insert a loose winding or covering of wire mesh. I also embed, preferably in horse-shoe shape, a small tight coil of wire mesh, lapped outside of the wood insert. I find it 30 desirable in some cases to have a layer of cloth molded close to the striking face and to the base of the club, and in some cases to have a layer of flat wire mesh set in from the top surface of the club.

35 I mold a hollow tube or socket in the composition by forming a tight winding of cord or cloth directly on the tube and painting this with the phenol varnish. Outside of this tube or socket and spaced therefrom, I 40 embed a tube of wire mesh, so that after the molding pressure is relieved, the composition between the tube and the socket will be under compressive stresses. At the top edge of the stem of the club I may insert a strip 45 of sheet fibre, painted with the phenol cement. This is to protect the sharp or somewhat feather edges from chipping.

The shaft of steel and preferably tapered at the end, is connected to the socket of a 50 wooden club head or the socket of the molded club head by having a very tight and close winding of strong cord on the tapered part of the shaft. The ends of this cord may be secured by any suitable way and is preferably in one layer. The cord winding is given a coat of phenol cement or suitable

glue and inserted in the wooden or the metal socket.

My invention will be more readily understood from the following description and 60 drawings, in which:

Figure 1 is a section of a wooden golf-club with a steel shaft handle secured to the socket of the club, in accordance with my 65 invention.

Figure 2 is a horizontal section through a molded club as on the line 2—2 of Figure 3, in the direction of the arrows showing the wood insert block and the various reinforce- 70

ments.

Figure 3 is a vertical section of the molded club as on the section 3—3 of Figure 2, and showing the metal socket with reinforcement there around and a steel shaft inserted in the socket in a manner similar to that of 75 Figure 1.

Reference is first directed to the manner of securing the shaft in a socket. The shaft 1 is usually made with a taper 2, both being hollow around the taper portion of 80 the shaft. I make a winding 3 of string or cord tightly wound and placed with the windings close together. This cord may be secured at the ends of the windings to the shaft in any suitable manner, as by half-hitches. When this shaft, thus prepared, is to be secured to a wood golf-head 4, the winding is covered with a suitable glue of 85 which some forms of phenol insulating cements are suitable. The shaft is then inserted in the socket 5. I do not rely on any screws or other fastening elements as the cord gives a sufficient frictional engagement 90 on the shaft and the glue sufficient adhesion to the socket. A plug 6 may be secured to 95 the lower end of the shaft to fill the socket and give a finish.

The large number of turns of the cord on the shaft give sufficient frictional resistance with the shaft as well as with the metal tubular socket of Figure 3. The gluing of the shaft to the head could be similar in either the wooden club of Figure 1 or the phenol composition club of Figures 2 and 3.

100 The formation of the phenol composition club and its construction is as follows:—The composition is indicated by the numeral 10, having a wooden block 11 inserted in about the middle of the composition. This block has a winding thereabouts 12, of cord or an open mesh cloth. Both the block and the cord are covered with a phenol insulating 105 110

varnish or cement. Outside of the block and encircling it is a wrapping 13, preferably of wire mesh. This is spaced from the block so that when the golf-head is molded under the high pressure used, in such operation, compressing the block: and when the pressure is relieved the composition 14, between the block and the mesh, will be under compressive stresses.

10 A tightly wound coil of wire mesh is inserted around the body portion of the club head, somewhat in horseshoe shape as indicated in Figure 2. A flat wire mesh reinforcement 16 is preferably placed across the 15 upper portion of the club head. Along the striking face and bottom I preferably use a layer of cloth of open mesh coated with phenol varnish. This is placed in the mold so that it will be substantially in the outside 20 face or what might be termed the skin of the club.

The socket for the shaft 1 is constructed as follows:—A metal tube 17 of substantially the same taper as the taper 2 of the shaft 1, 25 has a tight winding 18 of cord extending substantially from one end to the other. An open mesh fabric tightly stretched will also be sufficient, the cord or fabric being painted with the phenol varnish. A tube 19 of wire 30 mesh encircles the socket and is spaced therefrom in order to maintain, to a certain extent, the composition 20 between the socket and the mesh tube, under compressive stresses when the molding pressure is relieved. At the sharp edges I may insert a 35 layer of sheet fibre 21 such as heavy paper painted with phenol varnish in order to protect the edge from chipping.

The shaft 1, after being tightly wrapped 40 at its tapered end with the cord 3 and the cord given a coating of adhesive, is attached to the club head by forcing the tapered end into the socket 17 of the moulded head 10 and is firmly held in place when the adhesive hardens.

For some types of clubs it would not be necessary to use all the reinforcements shown, but these can be altered to suit different types and the reinforcement situated to give proper balance. Where I use the term "wooden block" it is understood that any suitable resilient filler may be used to which the phenol composition can be made to cling. However, a suitable type of wood gives considerable resiliency to the club head.

Having described my invention, I claim:—

1. A molded phenol composition golf-club having a filler block of wood with a winding cord or cloth around the wood, the wood and cord or cloth being coated with a phenol varnish or cement.

2. A molded golf-club as claimed in claim 1, having in addition a reinforcement of wire mesh surrounding the wood filler block.

3. A molded golf-club as claimed in claim 1, having a reinforcement of tightly coiled wire mesh fabric in the body of the composition.

4. A molded golf-club as claimed in claim 1, having a reinforcement of sheet fibre material coated with phenol cement inserted in the sharp corners of the club.

5. A molded golf-club as claimed in claim 1, having a reinforcement of cloth fabric inserted in the composition immediately inside of the striking face.

6. In a molded phenol composition golf-club, a socket comprising a metal socket tube with a winding of cord or cloth around the 75 socket tube, said cord or cloth being coated with a phenol varnish or cement.

7. A molded golf-club as claimed in claim 6, having in addition a tube of wire mesh surrounding the socket tube and embedded 85 in the composition spaced slightly from the tube.

In testimony whereof I affix my signature.

EDWARD L. HUBBARD.
